UNITED STATES PATENT OFFICE.

CHARLES A. NAGLE, OF ST. LOUIS, MISSOURI.

SAFETY ATTACHMENT FOR PNEUMATIC TOOLS.

1,219,140.

Specification of Letters Patent. Patented Mar. 13, 1917.

Application filed March 24, 1916. Serial No. 86,443.

To all whom it may concern:

Be it known that I, CHARLES A. NAGLE, a subject of the King of Great Britain, residing at St. Louis, State of Missouri, have 5 invented certain new and useful Improvements in Safety Attachments for Pneumatic Tools; and I do hereby declare the following to be a full, clear, and exact description of the invention, such as will enable 10 others skilled in the art to which it appertains to make and use the same.

This invention relates to a safety attachment for pneumatic tools, and particularly to an attachment for pneumatic riveter 15 which is designed for preventing the projection of the riveting tool from the casing of the pneumatic riveter, in case the head of the tool should slip off a rivet during the operation of the riveter.

20 Another object of this invention is to provide a safety attachment as specified which includes a pair of pins which extend through the casing of the riveter and project into an annular groove which is formed 25 in the shank of the riveting tool and also to provide means for holding the pins in their proper positions against accidental withdrawing movement.

With the foregoing and other objects in 30 view this invention consists in such novel features of construction, combination and arrangement of parts as will be hereinafter more fully described illustrated in the accompanying drawing and claimed.

35 In describing the invention in detail reference will be had to the accompanying drawings wherein like characters designate like or corresponding parts throughout the several views, and in which:—

40 Figure 1 is a side elevation of a fragment of a riveter showing the improved safety attachment applied thereto.

Fig. 2 is a longitudinal section through the fragment of the riveter.

45 Fig. 3 is a horizontal or cross section on the line 3—3 of Fig. 1.

Fig. 4 is a detail perspective view of one of the pins used in the construction of the riveter showing it connected to its supporting head, and

50 Fig. 5 is a detail fragmentary view of the means for holding the pins in their proper place.

Referring more particularly to the drawings, 1 designates the casing of a pneumatic

riveter, of the "Rich" type, in which is seated the shank 2 of the riveting tool 3.

The shank 2 is provided with an annular groove 4 formed therein into which the ends of pins 5 and 6 extend. The pins 5 and 6 extend through openings 7 and 8 which are formed in the casing 1 and they have their outer ends screw threadably seated in blocks 9 and 10. The blocks 9 and 10 are provided with laterally extending flanges 11, 60 against the outer surfaces of which the in-turned edges of a pair of semicircular binding members 12 and 13 engage. The binding members 12 and 13 are constructed of sheet metal and have their edges turned inwardly as clearly shown in Fig. 2 of the drawings, for engagement with the outer surfaces of the flanges 11 of the blocks 10. The ends of the members 12 and 13 are upturned and provided with openings 14 as 65 clearly shown at 15 in Fig. 5 of the drawing. The handles 16 of pivotally mounted locking levers 17 project through the openings 14, as clearly shown in Fig. 3 of the drawings. The locking levers 17 are provided with cams 18, which cams are pivotally connected as shown at 18^a to the members 12 and 13 respectively. The innermost portions of the cams 18 engage the outer surface of the casing 1 of the riveter. The 70 handles 16 are provided with offset portions 16^a intermediate their ends.

When it is desired to securely lock the members 12 and 13 in their proper position, after the entrance of a riveting tool 3 into 75 the casing 1, the device is positioned so that the pins 5 and 6 will be positioned vertically, and pressure is applied to the upper member of the members 12 and 13, which will, owing to the fact that portions of the cams 80 90 95 18 engage the periphery of the casing 1, rock the cams and the levers 16, causing them to spring outwardly and automatically lock, by the engagement of the offset portion 16^a with the upper portion of the upturned end 15 as clearly shown in Fig. 3 of the drawing. When it is desired to loosen the members 12 and 13 to permit the pins 5 and 6 to be moved outwardly for removing a riveting tool 3, the outer ends of the levers 16 are moved inwardly, so that the offset portions will be out of engagement with the upturned ends of the members 12 and 13, at which time the springs, herein-after described, will force the blocks 9 and 105 110

10, and consequently the members 12 and 13 outwardly, permitting of the removal of the riveting tool or anvil 3. The extreme outer ends of the levers 16 are slightly 5 curved, so as to prevent the levers from passing entirely through the openings 14.

The blocks 9 and 10 are provided with recesses 19 formed therein in which are seated 10 contacting spiral springs 20. The springs 20 engage the outer surface of the casing 1 and are provided for forcing the blocks 9 and 10 outwardly from the casing and moving the ends of the pins 5 and 6 out of the recess 4 when the binding members 12 15 and 13 are released.

In the foregoing description and in the drawing the improved safety attachment has been illustrated and described as applied to a pneumatic riveter but it is to be 20 understood that it may be applied to any suitable type of analogous tool wherein a reciprocating member is employed.

In reducing the invention to practice certain minor features of construction, combination and arrangement of parts may necessitate alterations to which the patentee is entitled provided such alterations are comprehended within the scope of what is claimed.

30. What is claimed is:—

1. In a device as set forth, the combination with a casing, and a reciprocatory tool having a shank mounted in said casing, said shank being provided with an annular recess, a plurality of pins extending through said casing and having their inner ends seated in said recess, means for holding said pins firmly in position and means for moving said pins out of said annular recess 40 immediately upon the release of said first named means.

2. In a device as set forth, the combination with a casing and a tool having a shank reciprocably mounted within said casing, 45 said shank being provided with an annular recess, of a plurality of pins extending through said casing and having their inner ends seated in said recess, blocks positioned exteriorly of said casing, the outer ends of 50 said pins being detachably connected to said blocks for holding said blocks in firm abutting engagement with portions of the outer surface of said casing for holding the inner ends of said pins in said recess, said blocks being provided with recesses extending 55 inwardly from their inner faces, springs mounted in said recesses, and adapted for forcing said blocks away from said casing

upon release of said first named means and means engaging the outer surfaces of said blocks for holding them in firm abutting engagement with portions of the inner surface of said casing.

3. In a device as set forth, the combination with a tool casing, a reciprocatory tool having a shank mounted within said casing, said shank being provided with an annular recess, of a plurality of pins extending through said casing and having their inner ends seated in said annular recess, blocks 70 being positioned exteriorly of said casing, said pins having their outer ends detachably connected to said blocks, a pair of substantially semi-circular members engaging the outer surfaces of said blocks for binding the blocks in firm abutting engagement with portions of the outer surface of said casing for holding the inner ends of said pins in said recess, means for moving and holding said semi-circular members into a locking 75 position, said means operable for moving said semi-circular members out of a locking position with respect to said blocks.

4. In a device as set forth, the combination with a tool casing, a reciprocatory tool having a shank mounted within said casing, said shank being provided with an annular recess, of a plurality of pins extending through said casing and having their inner ends seated in said annular recess, blocks 80 being positioned exteriorly of said casing, said pins having their outer ends detachably connected to said blocks, a pair of substantially semi-circular members engaging the outer surfaces of said blocks for binding the blocks in firm abutting engagement with portions of the outer surface of said casing for holding the inner ends of said pins in said recess, means for moving and holding 85

90 said semi-circular members into a locking position, said means operable for moving said semi-circular members out of a locking position with respect to said blocks, 95 said blocks provided with recesses extending inwardly from their inner faces, and springs mounted in said recesses for forcing said blocks out of abutting engagement with said casing upon the movement of said semi-circular members into an unlocking position.

100 In testimony whereof I affix my signature in presence of two witnesses.

CHARLES A. NAGLE.
